Emil Bonnelbyche
ATTORNEY

UNITED STATES PATENT OFFICE

CARL OTTO, OF ESSEN-RUHR, GERMANY

HORIZONTAL COKE OVEN

Application filed August 13, 1929, Serial No. 385,561, and in Germany July 14, 1928.

The invention relates to horizontal chamber ovens intended for the production of gas and coke and having vertical heating flues in which a partition having perforations there-
 5 in is arranged between the passages supply-
 ing the heating gas and the combustion air. The object of these perforations is to obtain a certain pre-combustion owing to the heating gas and the air tending to mutually pass
 10 through the perforations, as it has been assumed hitherto. Now, it has been proved that the buoyancy, increased by the flame, of the preheated agents of combustion is so great that any material mutual passage of
 15 gas and air does not take place and a satisfactory pre-combustion is thus not obtained. The invention has for its object to obviate this drawback which object substantially is obtained by so designing the detachably su-
 20 perimposed bricks which form the partition that a mutual passage of gas and air must take place through each brick and the possibility is given to vary at will according to the number of the bricks the degree of the
 25 pre-combustion aimed at by this mutual passage.

The invention constitutes an adaption to horizontal chamber ovens of the measures de-
 30 scribed in my former application Ser. No. 159,611, which has resulted in Patent No. 1,787,490, issued January 6, 1931, and taken to obtain an efficacious pre-combustion of gas and air in vertical chamber ovens. With
 35 horizontal chamber ovens the application of the chamber bricks described in and pro-
 tected by this patent to the partitions of the horizontal flues that supply gas and air is impossible as most of the modern ovens do
 40 not possess these horizontal flues and, be-
 sides, a pre-combustion within these flues would provoke only an undesired increased heating of the oven floor.

In order that the invention can be more
 45 easily understood, a preferred embodiment

of the same is illustrated by way of example in the accompanying drawings in which

Figure 1 is a fragmentary vertical section through the parts under consideration of a horizontal chamber oven, and

Figure 2 is a horizontal section on line 2—2 of Figure 1. 50

Referring to these figures, *a* denotes the coke chambers which in the usual manner alternate with heating walls *b*, each of which is subdivided so as to form a plurality of heating flues *c*. On the bottom end of each flue *c* is provided a hole or perforation *d* to feed the heating gas and a hole or perforation *e* for the combustion air. The wall sep- 55
 arating the holes *d* and *e* has mounted thereon a plurality of separating bricks *f* engaging one another by tongue and groove and the bricks being removable through an aperture (not shown) at the front end of the respec- 60
 tive flue *c*. Each of these bricks *f* has two oppositely inclined transverse slots *f*¹ and *f*² arranged side by side and covered at their lower ends by projections *f*³. The combus- 65
 tion agents entering through the holes *d* and *e*, are dammed by the projections *f*³ and thereby enforced to stream in part through the inclined slots *f*¹ and *f*² and to mix with 70
 one another. 70

As clearly seen it is possible to vary within 75 wide limits the degree of pre-combustion aimed at by varying the number of the slotted bricks *f* of each pile.

I claim:—

1. A gas and air mixer particularly for so coke oven flues having an air and a gas perforation, comprising a plurality of super-
 80 posed bricks removably mounted in the flues and between the perforations, each brick hav-
 85 ing passages therein from one side thereof to the other through which the air and gas flows from one side of the flue to the other.

2. A gas and air mixer particularly for coke oven flues having an air and a gas per- 90
 95 foration, comprising a plurality of super-

posed bricks removably mounted in the flues and between the perforations, each brick having a pair of oppositely inclined passages therein from one side thereof to the other through which the air and gas flows from one side of the flue to the other and each passage having a projection in the brick to guide the air or gas into the passage.

In testimony whereof, I have signed my
name to this specification.

CARL OTTO.
